DESIGN FOR A BLOUSE

Sidney Levy, New York, N. Y.

Application December 28, 1937, Serial No. 73,896

Term of patent 3½ years

To all whom it may concern:

Be it known that I, Sidney Levy, a citizen of the United States of America, residing in city of New York, county of New York, and State of New York have invented a new, original, and ornamental Design for a Blouse, of which the following is a specification, reference being had to the accompanying drawing, forming part thereof.

Fig. 1 is a front view of a blouse, showing my new design.

Fig. 2 is a rear view thereof.

The characteristic feature of my design resides in the box pleats on the center portion of the blouse, in combination with the triangular tab on the bottom portion of the box pleats as shown.

I claim:

The ornamental design for a blouse substantially as shown and described.

SIDNEY LEVY.
